UNITED STATES PATENT OFFICE.

VERN SLATER, OF CHICAGO, AND GEORGE B. GUTHRIE, OF LOCKPORT, ILLINOIS; SAID GUTHRIE ASSIGNOR TO SAID SLATER.

LINK CUFF BUTTON AND LINK UNIT THEREFOR.

Application filed April 13, 1922. Serial No. 552,098.

To all whom it may concern:

Be it known that we, VERN SLATER and GEORGE B. GUTHRIE, both citizens of the United States, and residents, respectively, of 5 Chicago, in the county of Cook and State of Illinois, and of Lockport, in the county of Will and State of Illinois, have invented certain new and useful Improvements in Link Cuff Buttons and Link Units Therefor, of which the following is a specification.

This invention relates to improvements in link cuff buttons and more particularly embodies a uniquely constructed and finished 15 link unit therefor, formed of a novelly associated combination of elements, which said link unit may as a bodily whole or as a unitary device be facilely attached to and detached from button heads of the same or 20 varying designs if so desired.

With the ordinary rigidly fixed and non-extensible cross-bars for such types of cuff buttons, not only is it sometimes extremely annoying and quite difficult to attach the 25 buttons, especially to highly starched cuffs, without soiling the cuffs with unsightly spots or without wrinkling them with a buckling-like bending at their corners, but also it is frequently impossible for the 30 wearer to remove from his body the shirt, to which the cuffs are attached, without first detaching at least one of the button heads from the cuff, as the cuff will not slip over the hand if it is dimensioned for fairly snug 35 fitting.

Analogously, it is impossible for the wearer to pull up his shirt sleeves beyond a very limited distance, if the button heads are in their attached positions at both edges 40 of the cuff, but the wearer frequently desires to so pull up his sleeves, to position his cuffs well up beyond the hands and wrists and to comfortably maintain them so held up, under varying conditions such as when work- 45 ing, playing various sporting games, washing-up or otherwise, both to prevent the cuffs from becoming unduly soiled as well as to hold them out of the way for the sake of

freedom of motion and general comfort under such conditions.

As commonly practised therefore, the general custom has been to simply unfasten or detach one head of the link button from its complementary cuff corner and to fold or turn the cuff back and over several times 55 along the sleeve. This is manifestly undesirable, as it not only causes the formation of a bulky and uncomfortable roll, either immediately above or below the elbow, but also it not infrequently results in the dis- 60 lodgment and loss of the cuff button which is held dangling from one button head only.

In avoidance of this general custom, it has even heretofore been proposed, however, and 65 patents have doubtless been granted along such lines, to provide link cuff buttons with extensible cross-bars in the nature of tubular shanks attached at one end to a button head and telescoping at their other ends, which short shanks may be associated under 70 resiliently retractile tension, as by means of an ordinary elongated helicoidal spring or analogous elastic element extending along 75 therein, but the pair of short tubular shanks conjointly provide the shank or cross-bar proper of the button, and being of a sliding or telescoping character they must be straight and not of the curved formation desired for link buttons. Furthermore, it is manifest that in order to telescope and contain a retractile spring inside, these tubular shanks would have to be of comparatively 80 large diameter, they would have no freedom of movement other than in a longitudinal direction, and they are wholly impractical 85 from a commercial viewpoint, as the link connection must be of comparatively small dimension in cross-section, whereas the structures just described are too bulky and cumbersome.

The primary aim of our invention has been to devise a link cuff button, or more particularly a link or shank unit therefor, wherein the extensible and retractile means are both combined as one and the same element which is also the shank itself, compris-

ing a one-piece and the only open-ended tubular member of the unit, consisting of a laterally unimpeded coil spring that houses a flexible extension limiting means, the ends of which latter preferably provide for interlocking means between the spring ends and capping elements therefor.

Other aims of our improvements are to provide such a shank unit as an assembled 10 whole, which is light in weight and of comparatively minimum cross-sectional dimension, simple and compact in structural assembly, comparatively inexpensive to manufacture and market, substantially effective 15 and durable in use, and which may if desired be facilely attached to and detached from button heads of varying designs.

The foregoing as well as other objects and advantages, however, will be more 20 clearly apparent as incidental to the following disclosure, and with these prefacing remarks, therefore, reference will now be immediately had to the accompanying drawings, illustrating certain practical embodiments of 25 the improvements, in which drawings all of the views are illustrated on an exceedingly large scale, of which—

Figure 1 is a plan view of the link or shank unit in contracted position; Figure 2 30 is an analogous view thereof as distended; Figure 3 is a longitudinal sectional view thereof as distended and attached to suitable cuff button heads; Figure 4 is a cross-sectional view on the line 4—4 of Fig. 3, but 35 only showing two of the spring coils for clearness of illustration; and Figure 5 is a cross-sectional view on the line 5—5 of Fig. 3.

The numeral 10 designates a pair of end 40 finishing caps which may mount attaching loops 11 in any suitable way, but these attaching loops 11 are preferably the terminal links of a light chain 12, although they might be other equivalent elements, the 45 heads of the caps 10 being slightly apertured to permit of the projection of the elements 11 therethrough. Obviously, however, if some form of flexible inextensible spring restraining means be employed, other 50 than the exact chain 12, then these attaching elements 11 could be loops or eyelets secured to the ends of such inextensible means.

Although, as to some features at least of the present improvements, our invention is 55 not intended to be limited to the use of the exact form of coiled spring illustrated, as the resiliently retractile shank of the button before referred to, however, owing to the spring being necessarily a light one, we at 60 present find it more expedient to employ a particular type of spring that is uniquely coiled, with a self-bracing or reinforcing effect as it were against undue torsional strains, and which will not, therefore, have 65 a tendency to unwind, as would a light

spring of exact circular convolutions, or become buckled or otherwise distorted, which would thus not only cause the spreading and weakening of the spring shank but would also displace the button heads out of line 70 with a twisted and unsightly appearance.

We accordingly prefer to use a spring 13 the coils of which, instead of being circular, provide a plurality of angularly bent arms forming apices or corner angles therebetween that are disposed in stepped spiral relation relatively to each other and the arms they oppose. The end coils of this spring are indicated at 14 and at their extremities provide the inwardly bent or 80 radial terminal arms or ends 15, for functioning as hereinafter described.

In the drawings, the coils of the spring are illustrated as of pentagonal form, although they obviously may be in the form of 85 squares, triangles or of other polygonal shapes, and, although at Fig. 4 only two such coils are shown, to avoid undue crowding of the view, it will be clearly understood that the apices, generally indicated by the 90 numeral 18, are disposed in stepped spiral relation relatively to the analogous apices, as for instance 16 and 17, and the arms therebetween which they oppose, thus providing a bracing, trussing or reinforcing series 95 of angular corners disposed spirally around the body of the spring, which likewise form a corresponding spiral depression 19 of unappreciable depth.

In assembling these parts as a link or shank unit for link cuff buttons, the spring 13 is caused to contain or encompass the chain 12 with the radial terminal arms 15 of the spring passing through the end links 11 of the chain. The end finishing caps 10 are then fitted over the spring ends with the terminal links 11 projected through the head apertures in the caps, and the projecting portions of the end links may then be slightly spread to prevent their return 110 through said apertures. Thus it will be observed that the complementary chain ends, the spring ends and their finishing caps are securely anchored together, and the shank as 115 a unit may be attached to and detached from any suitably formed link button heads.

At Figures 3 and 5, we have shown the link or shank unit in association with a pair of button heads to provide a complete link cuff button, wherein 20 designates the button heads and 21 indicates a fastening member secured to the inside face of each button head, which fastening members may have central depressions for receiving the end links 11, and one end of which may be 125 left unfastened for slipping an end link thereover. This, however, is merely illustrative and forms no particular feature of the invention in itself.

From all of the foregoing, it is believed 130

- that the great utility and full advantages of said spring, and capping members for housing the ends of said spring, the said spring providing radial terminals projecting through the end links of said chain, for conjointly anchoring the complementary ends 70 of said chain and said spring and their capping members, with the extremities of said chain protruding through and outwardly beyond said capping members.
- 5 understood that we do not wish to unnecessarily restrict ourselves to all of the details exactly as disclosed, excepting as they may come within the terms of the ensuing claims, or an equivalent combination of elements, or 10 after a fair interpretation thereof in the light of the specification if necessary, as it is obvious that some minor alterations might be made without departing from the gist of the invention.
- 15 What we do claim, as new and patentable, is:—
1. A shank unit for link cuff buttons embodying an elongated coil spring, an inextensible flexible spring restraining element 20 extending longitudinally therein and of greater length than said spring, and capping means for housing the ends of said spring, the said elements providing means for conjointly anchoring the complementary 25 ends of said flexible element and said spring and their capping members.
  2. A shank unit for link cuff buttons embodying an elongated coil spring, an inextensible flexible spring restraining element 30 extending longitudinally therein and of greater length than said spring, and capping means for housing the ends of said spring, the said elements providing means for conjointly anchoring the complementary ends 35 of said flexible element and said spring and their capping members, with the extremities of said flexible element projecting through and outwardly beyond said capping members.
  3. A shank unit for link cuff buttons embodying an elongated coil spring and an inextensible flexible spring restraining element 40 extending longitudinally therein and of greater length than said spring, the said 45 flexible element providing end loops and the said spring providing radial terminals projecting through said end loops, for anchoring the complementary ends of said flexible element and said spring.
  4. A shank unit for link cuff buttons embodying an elongated coil spring, a spring 50 extension limiting chain extending longitudinally therein and of greater length than said spring, and capping means for housing 55 the ends of said spring, the said elements providing means for conjointly anchoring the complementary ends of said chain and said spring and their capping members, with the extremities of said chain protruding 60 through and outwardly beyond said capping members.
  5. A shank unit for link cuff buttons embodying an elongated coil spring, a spring 65 extension limiting chain extending longitudinally therein and of greater length than
6. A shank unit for link cuff buttons embodying an elongated coil spring, an inextensible flexible spring restraining element 75 extending longitudinally therein and of greater length than said spring, and means for conjointly anchoring the complementary 80 ends of said flexible element and spring, the said spring being formed of coils having a plurality of angularly bent arms providing apices which are disposed in stepped relation spirally of the spring body. 85
7. A shank unit for link cuff buttons embodying an elongated coil spring, an inextensible flexible spring restraining element 90 extending longitudinally therein and of greater length than said spring, and capping members for housing the ends of said spring, the said elements providing means for conjointly anchoring the complementary 95 ends of said flexible element and said spring and their capping members, and the said spring being formed of coils having a plurality of angularly bent arms providing apices which are disposed in stepped relation spirally of the spring body.
8. A shank unit for link cuff buttons embodying an elongated coil spring, a spring 100 extension limiting chain extending longitudinally therein and of greater length than said spring, and capping means for housing the ends of said spring, the said elements providing means for conjointly anchoring the complementary ends of said chain and said spring and their capping members, with the extremities of said chain protruding 105 through and outwardly beyond said capping members, and the said spring being formed of coils having a plurality of angularly bent arms providing apices which are disposed in stepped relation spirally of the spring body. 110
9. A shank unit for link cuff buttons embodying an elongated coil spring, a spring 115 extension limiting chain extending longitudinally therein and of greater length than said spring, and capping members for housing the ends of said spring, the said 120 spring providing radial terminals projecting through the end links of said chain, with the extremities of said chain protruding through and outwardly beyond said capping members, and the said spring being formed of 125 coils having a plurality of angularly bent arms providing apices which are disposed in stepped relation spirally of the spring body.
10. In link cuff buttons, the combination 130

of a shank unit therefor embodying an elongated coil spring, a spring extension limiting chain extending longitudinally therein and of greater length than said spring, and 5 capping members for housing the ends of said spring, with the end links of said chain protruding outwardly thereof, the said spring providing radial terminals project-

ing through said end links inside of said capping members, and button heads attached 10 to said end links outside of said capping members.

In testimony whereof, we affix our signatures.

VERN SLATER.
GEORGE B. GUTHRIE.
